UNITED STATES PATENT OFFICE

98,876

DESIGN FOR A CANDLESTICK

William F. Liska, Chicago, Ill., assignor to Holland Brass Works, Incorporated, Chicago, Ill., a corporation of Illinois

Application January 15, 1936, Serial No. 60,586

Term of patent 7 years

To all whom it may concern:

Be it known that I, William F. Liska, a citizen of the United States, residing at Chicago, in the county of Cook and State of Illinois, have invented a new, original, and ornamental Design for a Candlestick, of which the following is a specification, reference being had to the accompanying drawing, forming a part thereof.

Referring to the drawing:

Fig. 1 is a front elevational view; and

Fig. 2 is a plan view of a candlestick showing my new design.

I claim:

The ornamental design for a candlestick, as shown.

WILLIAM F. LISKA.
